Primary Examiner — Brett Miller

(57) **CLAIM**

The ornamental design for a bridge as shown and described.

DESCRIPTION

1. Bridge

1.1 : Front

1.2 : Back

1.3 : Left

1.4 : Right

1.5 : Top

1.6 : Bottom

1.7 : Perspective

1.8 : Perspective

Broken lines in the reproductions show matter which does not form part of the claimed design and for which protection is not sought. The drawings include symbolic break lines in FIG. 1.1, 1.2, and 1.5-1.8. Any portion between the break lines forms no part of the claimed design.

1 Claim, 8 Drawing Sheets
